(57) **CLAIM**

The ornamental design for pre-cut trimmer line for string trimmer, as shown and described.

DESCRIPTION

1. Pre-cut trimmer line for string trimmer

1.1: Front

1.2: Back

1.3: Right

1.4: Left

1.5: Top

1.6: Bottom

1.7: Perspective

The parts shown by means of broken lines in the reproduction are not part of the claimed design.

1 Claim, 4 Drawing Sheets
